CLAIM

The ornamental design for an intelligent transporting robot (second generation), as shown and described.

DESCRIPTION

FIG. 1 is a front view of the new design; FIG. 2 is a back view of the new design; FIG. 3 is a left view of the new design; FIG. 4 is a right view of the new design; FIG. 5 is a top view of the new design; FIG. 6 is a perspective view 1 of the new design; and, FIG. 7 is a perspective view 2 of the new design.

The dot-dash broken lines represent the bounds of the claimed design while all other broken lines are directed to environment and are for illustrative purposes only; the broken lines form no part of the claimed design.
